(57) CLAIM

The ornamental design for an insert base for battery carrying tray, as shown and described.

DESCRIPTION

FIG. 1 is a front, top, and left side perspective view of an insert base for battery carrying tray, showing the claimed design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view showing the insert base for battery carrying tray in use; and,

FIG. 9 is an exploded perspective view of FIG. 8.

The broken lines shown in FIGS. 8 and 9 depict environment and form no part of the claimed design.
